2 SHEETS—SHEET 2.

UNITED STATES PATENT OFFICE.

HENRY W. SCHWARZ, OF MART, TEXAS.

WINDOW SASH AND CURTAIN OPERATING MECHANISM.

1,293,213.

Specification of Letters Patent.

Patented Feb. 4, 1919.

Application filed October 25, 1917. Serial No. 198,447.

To all whom it may concern:

Be it known that I, HENRY W. SCHWARZ, a citizen of the United States, residing at Mart, in the county of McLennan, State of Texas, have invented certain new and useful Improvements in Window Sash and Curtain Operating Mechanism; and I do hereby declare the following to be a full, clear, and exact description of the invention, such as will enable others skilled in the art to which it appertains to make and use the same.

This invention relates to window structure, and has particular reference to combination window sash operating devices and window protecting mechanisms.

The object of the invention is to construct a window structure which embodies, in addition to the usual sashes, a shade, screen and curtain combination, together with means for actuating the various parts of the combination, the various elements forming parts of a built-in organization which is therefore, in the main, shielded from view in the window frame.

A further object of the invention is to associate with the window sash operating mechanism a burglar alarm which will be automatically sounded when the sashes are opened after the alarm mechanism has been set to operative position.

With the above objects in view, and such others relating to the details of construction as may hereinafter appear, my invention will now be fully set forth and described, reference being had to the accompanying drawings.

In the drawings:—

Figure 1 is a front elevation of a window frame,

Fig. 2 is an elevation showing the window casing facing removed,

Fig. 3 is a vertical section on line 3—3 of Fig. 2,

Fig. 4 is a section on line 4—4 of Fig. 2,

Fig. 5 is a section on line 5—5 of Fig. 2,

Fig. 6 is a detail view of an alarm mechanism,

Fig. 7 is a vertical section showing a modification and

Fig. 8 is a longitudinal section, in detail, of a clutch.

Referring more particularly to the drawings, 1 represents the stiles and 2 the cross pieces of the window frame, the stiles slidably carrying the upper and lower sashes 3 and 4 respectively. Extending through

the stiles, transversely of the frame and at a height which approximates the meeting point of the upper and lower sashes in their closed positions, is a shaft 5 which carries 60 the pinions 6. The pinions 6 are disposed between the vertical elements of the sashes 3 and 4, and mesh with opposing racks which are set into the sashes in opposing relation, so that with the rotation of the 65 shaft 5, the lower sash will be raised and the upper sash will be simultaneously lowered.

The ends of the shaft extend into the vertical chambers at each side of the window 70 casing, and upon one side has keyed upon the end a bevel gear 7 which meshes with a bevel pinion 8 carried by a transverse crank shaft 9, the latter having one end extended through the face of the casing into the room. 75 Upon its inwardly extended end, the crank shaft 9 is provided with a hand crank 10, and also a ratchet disk 11 which may be engaged by a pawl 12 to lock the mechanism against return rotation, provision for which 80 is made as follows.

Mounted upon each end of the shaft 5 is a drum 13 around which a cable 14 is secured, the opposite end of each of the cables 14 being secured to one end of a coil 85 spring 15. The coil springs 15 are secured to the bottom of the window casing, and tend to rotate the shaft 5 into that position which will mark the closing of the sashes, so that when the crank shaft 9 is operated to 90 open the sashes, it is necessary to lock them in open position by the engagement of the pawl 12 with the teeth of the ratchet disk 11.

The shaft 9 is also intended for use in operating a combination screen, shade and shield 95 mechanism. For this reason, the bevel gear 7 is slidable on the shaft 5, so that clutch elements 16 upon its inner face may be carried into and out of engagement with the corresponding clutch elements 17 upon the 100 opposing face of the drum 13. A spring 18 normally throws the gear 7 away from the drum 13, and in order to permit the advance of the gear toward the drum the teeth of the former are elongated, and the pinion 105 8 is movable with relation to the gear 7 by reason of a sliding action of the crank shaft 9 against the normal tendency of a spring 19 to throw the shaft 9 inwardly. Thus, by drawing the shaft 9 toward the operator, 110 the teeth of the pinion 8 cam against the extended teeth of the gear 7 and throw the

clutch elements 17 and 16 into engagement, after which the rotation of the shaft 9 will operate the sashes. When the clutch elements are disengaged, it is necessary to have 5 a further locking device to hold the drums 13 when the sashes are open. For this purpose, a pair of levers 20 are pivotally mounted through the facing of the window casing and upon their inner ends are provided 10 with pawl members 21 which are adapted to interlock with teeth formed upon one of the end flanges of the drums 13, the teeth 21' being directed to prevent the rotation of the drums under the action of the 15 springs 15.

As a means to warn the occupants of the house of burglarious attempts to enter the window, I have mounted a plunger 22 within a casing formed by guides 23 upon the 20 inner face of the casing, the upper end of the plunger carrying a clapper 24 which may strike against a bell 25 to sound an alarm. Extending through the facing of the casing and pivoted to rock with relation thereto, is a pair of links 26 whose outer 25 ends pivotally engage the plunger 22. The inner ends of the links are transversely connected by a bar or pin 27 which stands in the path of movement of the teeth 27' formed upon the flange of the corresponding 30 drum 13, so that as said teeth strike the pin 27 the links 26 are rocked to reciprocate the plunger and sound the bell. A guide pin 28 extends through the guides 23 and 35 also through an arcuate slot 29 in the plunger 22, and the action of the teeth 27' is against the influence of the action of the spring 30 to determine the operative or inoperative position of the alarm, the clapper 40 per 24 is carried by a crank arm vertically pivoted in the upper end of the plunger 22 so that the clapper may be swung away from a position where it will contact the bell into an inactive position.

45 As a modified form of the means for holding the windows in whatever position of adjustment they may be caused to assume, a crank 5' may be bent into the shaft 5 at each side of the frame, and may have attached thereto as shown in Fig. 7 the end 50 of a spring 15', these springs tending to hold the cranks 5' downwardly below the shaft. Thereby, the rotation of the latter is prevented against any except a positive 55 rotative influence.

Extending across the upper end of the casing, above the window opening is a roller 31 which parallels a take-up roller 32 which extends below the window opening. Within 60 an inclosed framing which is built outside of the window casing there is also provided a third roller 33, which normally holds a continuous length of screening 34, a length of shade material 35 and a flexible shield or 65 metal curtain structure 36. The roller 31

has its bearing shaft extended so that there can be fixed thereon a sprocket wheel 37 around which is passed a sprocket chain 38 whose opposite end passes over a series of sprocket teeth formed on the hub of the 70 bevel gear 7. Again, the bevel gear 7 has a second set of sprocket teeth which receives a chain 39, whose opposite end passes over a sprocket wheel 40 fixed upon the shaft of the lower roller 33. Thus, the actuation 75 of the bevel gear 7 also causes the rotation of the rollers 31 and 33 to extend the elements of the combination flexible strip. The upper roller 31 is provided with a winding spring 41 which tends to return the flexible strip to the upper end of the window casing, and a sprocket chain 42 which passes over suitable sprocket wheels 43 and 44 on the roller 31 and the roller 33 respectively 80 actuates the latter so that the strip is wound thereon when the rollers are released by the lifting of the pawl 12 from the ratchet disk 11.

It will be primarily noted from the foregoing description that all of the parts of 90 the mechanism are controlled from a single operating device, and that the flexible strip may be actuated either in combination with the sashes, or may be adjusted independently of the latter. The elements of the 95 flexible strip operate across the outside of the window opening, within suitable vertical guide-ways, and, in accordance with the weather conditions or other governing circumstances, the screen, the shade or the 100 metal shield structure may be extended across the window opening. Furthermore, the metal shield structure may serve as an awning or a fire shield.

It will be apparent from the foregoing 105 description that I have provided a complete and effective window sash operating mechanism and protecting devices, whose selective relationship, and unitary control render it possible to meet the various conditions of weather and other circumstances.

What I claim as my invention is:—

1. In a window structure, upper and lower sashes, a shaft extending across the structure between the sashes, pinions upon the shaft, rack bars carried by the sashes and meshing with the pinions, rollers mounted at the top and bottom of the window structure, a flexible strip operative over the rollers, operating connections extending from the shaft to said rollers, and means for operating the shaft to actuate the sashes and also to actuate the rollers.

2. In a window structure, upper and lower sashes, a shaft extending across the 125 structure between the sashes, pinions upon the shaft, rack bars carried by the sashes and meshing with the pinions, rollers mounted at the top and bottom of the window structure, a flexible strip operative 130

over the rollers, operating connections extending from the shaft to said rollers, means for operating the shaft to actuate the sashes and also to actuate the rollers, 5 and means normally tending to close the sashes against the actuating movement of said shaft.

3. In a window structure, upper and lower sashes, a shaft extending across the 10 structure between the sashes, pinions upon the shaft, rack bars carried by the sashes and meshing with the pinions, rollers mounted at the top and bottom of the window structure, a flexible strip operative 15 over the rollers, operating connections extending from the shaft to said rollers, means for operating the shaft to actuate the sashes and also to actuate the rollers, means normally tending to close the sashes 20 against the actuating movement of said shaft, and means for locking the sashes in open position.

Copies of this patent may be obtained for five cents each, by addressing the "Commissioner of Patents, Washington, D. C."

4. In a window structure, upper and lower sashes, a shaft extending across the structure between the sashes, pinions upon 25 the shaft, rack bars carried by the sashes and meshing with the pinions, rollers mounted at the top and bottom of the window structure, a flexible strip operative over the rollers, operating connections ex- 30 tending from the shaft to said rollers, means for operating the shaft to actuate the sashes and also to actuate the rollers, and independent means normally tending to close the sashes and wind the rollers in the 35 opposite direction against the actuating tendency of the shaft.

In testimony whereof, I affix my signature in the presence of two witnesses.

HENRY W. SCHWARZ.
